UNITED STATES PATENT OFFICE.

ALEX M. LIFSHITZ, OF BROOKLYN, NEW YORK.

ELECTRICAL ATTACHMENT FOR MUSICAL INSTRUMENTS.

Application filed August 5, 1926. Serial No. 127,418.

My invention relates to electrical attachments and has a particular reference to electrical devices adapted to operate musical instruments of percussion type, such as drums, 5 gongs, xylophones etc.

The object of my invention is to provide a series of electrical devices with electrical switches in the form of pedals, the devices being easily attached to suitable musical instruments, the musician would be able to play on these musical instruments by simply operating the pedal switches. This arrangement would leave the musician's hands free to play on some other instrument, such as 15 a piano, violin etc.

With this object in view I provide my electrical percussion devices with means to attach them to the musical instruments, also with means to adjust their position for proper operation. The pedal switches I arrange 20 so that a musician could operate them with the heel or toe of his foot or both, in order to produce different effect, for instance, a single strike or a continuous vibration. 25

My invention is more fully described in the accompanying specification and drawing in which—

Fig. 1 is an elevation partly in section of a large drum and gong with different electrical percussion devices and with pedal switches. The electrical connections are shown diagrammatically. Fig. 2 is an elevation of a small drum with two different 30 percussion devices, the electrical connections being omitted on this drawing. Fig. 3 is an elevation of an electromagnetic percussion device, Fig. 4 is a bottom view of same, Fig. 5 is an elevation of same in an inclined position with electrical connections and switches shown diagrammatically, and Fig. 6 is a 35 similar view showing different arrangement of switches.

My attachment consists of an electromagnet 1 mounted on a yoke 2. A screw 3 threaded into the bottom end of the magnet core 4 clamps the magnet to this yoke. The upper end of the yoke is bent over and is provided with a large hole into which a 40 threaded bushing 5 is fitted with an insulation 6. A contact screw 7 is screwed into the bushing 5. The end of the screw rests against a contact spring 8 attached to an armature 9 pivotally mounted on pivots 10 on the yoke 2. A resilient rod 11 is attached to the end of the armature and is provided with

a mallet or ball 12 at the end. The rod 11 is preferably (although not necessarily) made of a resilient material in order to produce a clear sound from the musical instrument. For this purpose the magnet is attached in such a position in relation to the drum surface 13, for instance, that the ball 12, when armature is fully attracted by the magnet, still stays a short distance away 60 from the drum. Only when the armature is attracted quickly by the magnet the ball by inertia causes a certain flexure of the rod 11, striking the drum surface and immediately rebounding back. 65

The lower portion of the yoke 2 has a hole for the screw 3. When the latter is released the yoke with the mallet can be turned in any position around flexible supporting members 14 which are also provided with 70 holes for the screw 3. Another end of the member or strap 14 is pivotally mounted on a pin 15 fitted into holes 16 in lugs 17 on a clamp 18.

The upper end of this clamp is provided 75 with a hook 19 adapted to fit the outer edge of a drum 20 (shown with dotted lines). The lower end of the clamp body is threaded for an extension rod 21 supporting a lower hook 22, which may be fitted over the lower 80 edge of the drum (its lower hoop). The clamp is tightened by turning the screw rod 21 for which purposes it has a head 23 with holes 24. Or it may be made hexagonal or 85 square for a wrench. 90

The supporting member 14' is attached with one end to the yoke 2 and the other is provided with an elongated slot 25 for the screw 3. With the screw 3 loosened the magnet may be shifted to different positions, 95 the screw 3 sliding in the slot 25 of the strap 14', and the strap 14 deflecting accordingly. By observing Figs. 3 and 5 it may be seen, that by moving the magnet away from the screw, it becomes inclined upon tightening 100 of the screw 3, as shown in Fig. 5. This causes the mallet to take a position closer to the drum surface. By moving the magnet closer to the clamp 18 the magnet becomes 105 tilted or inclined backwards, and the mallet will be moved away from the drum surface.

The magnet may be also turned around the screw 3 in order to adjust the position of the mallet on the drum. This is important 110 when several magnets are attached to the same drum (as shown in Figs. 1 and 2) in order to select the most advantageous mu-

tual positions for them to prevent their interference and to obtain the best sound.

The mallet is normally kept in a raised or inoperative position by means of a spring 26.

Fig. 5 shows a modified construction of the clamp 18' specially adapted for larger drums. In this case the clamp is provided with a lower hook 27 with a screw 28. The end of this screw has a pad 29 with which it presses against the lower edge of the drum hoop 20. The upper hook has also screw 30 with which the clamp is fastened to the upper edge of the hoop 20.

With the clamps as shown the magnet may be attached to any suitable musical instruments, such as gongs, drums, xylophones etc.

Fig. 2 shows two magnets attached to a small drum on a tripod 31. One of the magnets is provided with a regular mallet ball 12, and the other has a bunch of flexible thin rods which produce a special "wind" effect when operated. The magnets are shown with simple armatures without interrupting device and adapted to produce a single blow of the mallet every time when the circuit is closed.

Similar magnets are attached to the periphery of a large drum, Fig. 1 and are provided with contact screws 7 so as to produce a vibrating effect when operated, the contact screw with the contact spring 8 forming an ordinary circuit interrupting device.

Fig. 1 shows a gong 32 attached with a clamp 33 to the large drum. In addition to the vibrating magnets 1 it has a nonvibrating strong magnet 34 mounted inside of the base 35. The armature 36 operates a wire 37 attached to one end of a rocking member 38 pivotally mounted on a stand or support 39. The rocking member 38 has a resilient rod 11 with a ball 12 on the end. A spring 40 keeps the ball away from the gong in an inoperative position.

The gong is also provided with a silencer which consists of a soft pad 41 attached to an armature 42 of a magnet 43. A spring 44 tends to keep the pad pressed against the gong, and the silencer releases the gong only when the magnet is energized.

The large drum has a single large mallet 12 on a rocking member 45 with a retrieving spring 46 and an operating wire or rod 47 connected with an armature 48 of a strong double magnet 49 mounted inside of the base 35. The rocking member is supported on a stand or bracket 50.

The current is furnished by an electric battery 51 or similar source of electricity. The magnets 1 are operated by ordinary pedal or floor contact switches 52, shown diagrammatically in Fig. 1. Magnets 34 and 49 are operated by a pedal switch 53. A spring 54 is connected with one terminal of the battery 51, and a spring 55

with a contact plate 56 is connected through a coil of the magnet with another battery terminal. This switch is adapted to be operated by a toe of the foot 57 (shown with dotted lines in Fig. 1) of a musician.

A spring 58, which may be made as an extension of the spring 54, is connected with one terminal of the battery 51, and the contact spring 59—through the coil 43 of the silencer with another battery terminal. A pedal switch 60 operates the large magnet 49.

The operation of these devices is as follows. The operator uses his left foot to press the pedals 52, one at a time, in order to produce a vibrating sound of the gong. This sound will be damped or silenced, however, unless he presses the switch 53 with the heel of his right foot (contact points 58 and 59). With this latter switch closed, the magnet 43 pulls the armature 42 and brings the silencer or dampener 41 away from the gong into an inoperative position.

The right foot may be used to operate the large mallet with the magnet 34 which produces a single blow on the gong. By pressing the toe only the sound will be quickly silenced, but if the heel is pressed at the same time, then the sound will last for some time, gradually dying out.

The switch 60 may be operated by the right or left foot at the operator's convenience.

In the same manner the switches 1 of Fig. 2 are operated (the electrical connections are not shown).

Fig. 5 represents a modification. Here a battery of switches 61, 62, 63 and 64 are shown, all adapted to produce a single blow. This arrangement may be used, for instance, to operate a plurality of switches for a xylophone or cymbals.

The switch 61, however, is a master switch. In its normal position, as shown, it connects the other battery terminal 65 with the lead of the coil 1 which is also connected with the yoke 2. By pressing on this switch so as to close the contact 66, the contact point 67 becomes disconnected, and the circuit for all the other switches becomes closed through the vibrating contact points between the screw 7 and the spring 8. With this position of the master switch all other switches, when operated, will cause the corresponding magnets to vibrate.

Fig. 6 represents a modification of the pedal switch. The latter has three contact springs, 68, 69 and 70, connected with the magnet 1 as shown.

By pressing the switch 68 with the heel and the switch 69 with the toe, the circuit will be closed through the contact screw 7, causing the armature 9 to vibrate.

By shifting the foot so as to press the switch 70, the coil 1 will be energized directly, and the armature will be attracted to

the magnet, producing but one blow with the mallet 12. The switch 69 may be pressed without having any effect, however, on the operation of the magnet.

5 I claim as my invention:

1. In an electric attachment for musical instruments, the combination with a bracket adapted to be clamped to the hoop of a drum, flexible members extending from said 10 clamp and converging together at a distance from said clamp, a magnet, means to attach said magnet to said flexible members at the point of their convergence, means to change the angular position of said magnet in relation to said drum, and an armature with a mallet adapted to be operated by said magnet.

2. In an electric attachment for musical instruments, the combination with a bracket, 20 means to attach said bracket to a musical instrument, flexible members extending from the ends of said bracket and converging together at a distance from said bracket, a magnet, means to attach said magnet to said 25 flexible members at the point of their convergence, said members being provided with elongated apertures for said attaching means, means to change the relative lengths of said flexible members thereby changing the angu-

lar position of said magnet in relation to 30 said bracket, and an armature with a striking mallet adapted to be operated by said magnet.

3. In an electrical attachment for musical instruments, the combination with a bracket 35 of means to attach said bracket to a musical instrument, a magnet coil, an iron core in said magnet coil, said coil and said core forming a magnet, extension members extending from the ends of said bracket and 40 converging together at a distance from said bracket, means to attach one end of said core to said members at the point of their convergence, an armature with a mallet for 45 said musical instrument adapted to be operated by said magnet, a switch, electrical connections between said switch and said coil, interrupting contact members for said armature, a second switch, electrical connections between said second switch and said interrupting contact members, said switches 50 being adapted to be operated by a heel and by toes of a musician's foot.

Signed at Brooklyn in the county of Kings and State of New York this third day of 55 August A. D., 1926.

ALEX M. LIFSHITZ.
